(57) **CLAIM**

The ornamental design for a magnetic reading sensor, as shown and described.

DESCRIPTION

FIG. 1 is a front, top, and right side perspective view of a magnetic reading sensor showing the first embodiment of our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged partial view of FIG. 1 thereof;

FIG. 9 is a front, top, and right side perspective view of a magnetic reading sensor showing the second embodiment of our new design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is an enlarged partial view of FIG. 9 thereof;

FIG. 17 is a front, top, and right side perspective view of a magnetic reading sensor showing the third embodiment of our new design;

FIG. 18 is a front view thereof;

FIG. 19 is a rear view thereof;

FIG. 20 is a left side view thereof;

FIG. 21 is a right side view thereof;

FIG. 22 is a top view thereof;

FIG. 23 is a bottom view thereof; and,

FIG. 24 is an enlarged partial view of FIG. 17 thereof.

The broken lines set forth in the several figures illustrate portions of the magnetic reading sensor that form part of the claimed design.
